UNITED STATES PATENT OFFICE.

EDWARD J. BIRD, OF ASHLAND, KENTUCKY.

REDUCTION-FURNACE.

1,333,957.

Specification of Letters Patent. Patented Mar. 16, 1920.

Application filed June 12, 1919. Serial No. 303,602.

To all whom it may concern:

Be it known that I, EDWARD J. BIRD, a citizen of the United States, residing at Ashland, in the county of Boyd and State 5 of Kentucky, have invented certain new and useful Improvements in Reduction-Furnaces, of which the following is a specification.

This invention relates to reduction furnaces such as blast furnaces and the like and methods and apparatus for charging the same with material to be reduced therein.

In a furnace of this character it is important to keep the furnace top closed to prevent the escape of the gases which are forced through flues for preheating the air, also for generating the steam necessary for the operation of the furnace. Furthermore, the charge should be evenly mixed and distributed so that the coarse and fine material will be evenly affected by the ascending hot gases of the furnace.

The chief object of my invention is to provide a method and apparatus whereby a furnace may be charged and the charge evenly mixed and distributed so that the reduction will be uniform.

With the above and the related objects in view my invention comprises the method and 30 means hereinafter described, an embodiment whereof is illustrated in the accompanying drawings and is embraced within the scope of the appended claims.

In the said drawings:

35 Figure 1 is a sectional elevation of a blast furnace provided with my improvements;

Fig. 2 is a section on the line 2—2 of Fig. 1;

40 Fig. 3 is a section on the line 3—3 of Fig. 1;

Fig. 4 is a view similar to Fig. 2 showing a modified form of a distributor in connection therewith.

Referring more particularly to the drawings for a detail description of my invention, the furnace proper comprises a cylindrical metallic shell 5 filled with a refractory material, such as brick-work 6 or the like, and provided interiorly with a circumferential seat or shoulder 7. On top of the shell are mounted posts or pillars 8, the bases of the pillars being reinforced by metallic brackets 9. The pillars support a girder 10 provided with a central bearing 11. Centrally above said bearing is mounted a spider-like base 12 for a cylinder 13. The

cylinder is provided with a piston 14 having a shaft 15 provided with a worm thread 16 in mesh with a similar thread of the bearing 11. The furnace is provided interiorly 60 with a floor 17 braced by brackets 18, said floor being provided with a bearing 19 for the shaft 15. Suspended from the shaft 15 is a conical distributor 20 provided on its upper surface with ribs 21 and an interceptor 22 is supported by the shoulders 7 surrounding the rim of the distributor 20, which rim is projected slightly through the opening and in contact with the edge of the interceptor, said contacting portion of 70 the distributor being free of the ribs. The cylinder 13 is provided with ports connected with a steam pipe 23 adapted to supply steam on opposite sides of the piston, said pipe being connected with a steam supply 75 pipe 24 through a compound valve 25 adapted to be operated by ropes or wires 26. The cylinder is also provided with valve controlled exhausts 27. The floor 17 is provided with openings 28 and with track 80 rails 29.

The modified distributor shown in Fig. 4 is in every respect similar to the distributor shown in Fig. 2 except that it is provided with curved ribs 30.

The operation is as follows:—Assuming that the piston is at the upper end of its stroke the ore to be reduced is conveyed by car or other means to one of the openings 28 and is discharged through the same into 90 the furnace. The charge drops onto the interceptor, filling the triangular space between the said interceptor and the distributor 20. Steam is admitted through the upper port of the cylinder by operating the 95 valve by means of the ropes 26, this causes the piston to descend opening the valve of the lower exhaust and causing the shaft 15 to descend and at the same time to rotate in its worm bearing. The distributor 20 thus descends forming an opening through 100 which the charge escapes and, due to the rotary movement, the ribs 21 act as shovels forcing the charge from the interceptor onto the distributor and thence down into the 105 furnace causing it to drop in screw-like spiral spray so that it will spread and be deposited in a layer of uniform thickness. I thus provide equal freedom for the ascending gaseous matter and obtain uniform 110 melting with an economy of fuel and labor. When the entire charge has been released,

the valve 25 is operated for introducing steam at the bottom of the cylinder causing the piston to move upwardly in the cylinder opening the valve of the exhaust above it causing the distributor to move upwardly and closing the opening of the interceptor. The receiver is then ready for another charge.

Having thus described the invention, what is claimed as new is:

10. 1. The combination with a furnace having a feed opening in its top, of an interceptor in the furnace adjacent and below said opening, a distributor coöperating with said interceptor to control the flow past the same, and a single mechanism for moving said distributor from and to the interceptor and simultaneously rotating the distributor alternately in opposite directions.
20. 2. The combination with a furnace, of a floor extending over the top of the furnace and having a feed opening therethrough, an interceptor within the furnace below said floor, a shaft extending through said floor, a distributor on the lower end of said shaft controlling the flow past the interceptor, and means above the floor to rotate the shaft horizontally alternately in opposite directions and reciprocate it vertically.
30. 3. The combination with a furnace having a feed opening in its top, of a shaft extending vertically through the top of the furnace and having a threaded portion near its upper end, a distributor carried by the lower end of said shaft within the furnace,

an interiorly threaded stationary bearing above the furnace which receives the threaded portion of the shaft, and means acting on the upper end of the shaft for moving the shaft axially through the threaded bearing whereby as the shaft is reciprocated it will be rotated alternately in opposite directions.

4. The combination with a furnace having a feed opening in its top, of a vertically disposed cylinder disposed above the top of the furnace, a piston in said cylinder, a shaft depending from said piston through the top of the furnace, means for admitting fluid to the cylinder to reciprocate the piston therein, a distributor carried by the lower end of said shaft, and a threaded bearing for said shaft whereby the shaft will be rotated as it moves endwise with the piston.

5. The combination with a furnace, of columns erected thereon, a girder supported on said columns and having an internally threaded bearing therein, a shaft extending vertically through the top of the furnace and having a threaded portion near its upper end engaging in said bearing, a distributor on the lower end of said shaft, and means supported on said girder over said bearing for vertically reciprocating the shaft through the bearing whereby the shaft will be rotated alternately in opposite directions as it reciprocates.

In testimony whereof I affix my signature.
EDWARD J. BIRD. [L.S.]
